US00D598135S

(12) **United States Design Patent**
Mugge et al.

(10) **Patent No.:** **US D598,135 S**
(45) **Date of Patent:** **** Aug. 11, 2009**

(54) **MOLDED SURFACE OF A CONCRETE PRODUCT**

(75) Inventors: **Jimmie L. Mugge**, Inver Grove Heights, MN (US); **Jay J. Johnson**, Star Prairie, WI (US); **Howard Merriam**, Edina, MN (US)

(73) Assignee: **Anchor Wall Systems, Inc.**, Minnetonka, MN (US)

(**) Term: **14 Years**

(21) Appl. No.: **29/277,916**

(22) Filed: **Mar. 14, 2007**

(51) **LOC (9) Cl. 25-01**

(52) **U.S. Cl. D25/113**

(58) **Field of Classification Search** D25/102-118, D25/164; D21/484-491, 499-502; 405/284-286; 404/27-31, 37-39, 42; 52/503-505, 574-576, 52/596-608, 612

(57) **CLAIM**

The ornamental design for molded surface of a concrete product, as shown and described.

DESCRIPTION

FIG. 1 is a front elevational view of a molded surface of a concrete product according to our new design;

FIG. 2 is a right side elevational view thereof;

FIG. 3 is a left side elevational view thereof;

FIG. 4 is top view thereof;

FIG. 5 is a bottom view thereof; and,

FIG. 6 is a front perspective view thereof.

The broken lines in all views are included for the purpose of illustrating portions of the concrete product that form no part of the claimed design.

1 Claim, 6 Drawing Sheets
